Primary Examiner — Cathron C Brooks*Assistant Examiner* — Sharon S Oum*(74) Attorney, Agent, or Firm* — McGarry Bair PC(57) **CLAIM**

The ornamental design for a ceiling fan light kit, as shown and described.

DESCRIPTION

FIG. 1 is a bottom perspective view of a ceiling fan light kit; FIG. 2 is a top perspective view thereof; FIG. 3 is a top view thereof;

FIG. 4 is a bottom view thereof; and,

FIG. 5 is a front side view thereof, with rear, right, and left side views being mirror images thereof.

The broken lines illustrate environmental structure, and portions of the ceiling fan light kit. None of the broken lines form part of the claimed design.

1 Claim, 5 Drawing Sheets(56)
